US00D895531S

(12) **United States Design Patent** (10) **Patent No.:** **US D895,531 S**
(45) **Date of Patent:** **** Sep. 8, 2020**

(54) **OVERHEAD CONSOLE**

(71) Applicant: **VOLVO CAR CORPORATION**, Gothenburg (SE)

(72) Inventor: **Per Ryberg**, Vänersborg (SE)

(73) Assignee: **Volvo Car Corporation**, Gothenburg (SE)

(**) Term: **15 Years**

(21) Appl. No.: **29/694,482**

(22) Filed: **Jun. 11, 2019**

(30) **Foreign Application Priority Data**

Jan. 7, 2019 (EM) 005949112-0001

(51) **LOC (12) Cl.** **12-16**

(52) **U.S. Cl.**

USPC **D12/418**

(58) **Field of Classification Search**

USPC D12/415-420, 400, 195, 191, 106, 345, D12/96, 99; 312/246; 296/37.1-37.8, 296/70, 24.1, 24.2, 24.3, 137.1, 97.1, 296/97.2, 97.4, 97.5, 97.6, 97.7, 97.8, 296/180, 1; 224/311, 539, 281, 118.1, 224/275; D8/354; D14/451-452, 113, D14/132-133, 100; 248/278.1, 274.1, 248/284.1; D9/423; D3/319; 160/370.21, 370.23, 370.22; 180/90
